AKTIENGESELLSCHAFT, OF DRESDEN, GERMANY

CINEMA CAMERA

Application filed August 11, 1925, Serial No. 48,638, and in Germany September 5, 1924.

It is known in photographic apparatus to open the shutter by means of a time release after a period which can be set beforehand, so that the operator can bring himself into the picture. Since cinematographic apparatus have been adopted also by amateurs, it is desirable also in the case of these apparatus to take photographs by means of time releases.

According to the invention, this can be done by mounting in the interior of the cinematographic photographing apparatus a time release. This arrangement has the advantage that the release cannot get lost and that no manipulations are required, before 15 the photographs are taken, for securing it, as is the case in photographic apparatus. Moreover, the time release cannot get either damaged or forgotten during the transportation of the photographing cinematograph. The time 20 release could be mounted in the apparatus independently of the cinema driving gear, or also with a separate source of power, in such a manner, that it is driven by its driving gear. In this case, a separate spring winding gear 25 for the time release is not necessary. The connection of the time release to the driving gear of the cinematograph is then preferably effected in such a manner that when required it can be disconnected from the cinematograph 30 driving gear.

In the drawing:

Figure 1 shows in front elevation the cinematograph drive with a built-in time release in its operating position, the casing being 35 partly broken away;

Figure 2 is an enlarged front elevation of the release device of the time release in the disengaged position; and

Figure 3 is a fragmentary top plan view of 40 the time release in accordance with Figure 1, parts being shown in section.

The toothed wheel *a*, which is driven by the source of power of the cinematograph, is in engagement with the teeth of a stop disk *b* 45 with two diametrically opposite stop projections *c*₁, *c*₂. The release lever *d*, which serves for exposure by hand, i. e. without the time release, engages against the stop projection *c*₁ and can be released by hand in well-known fashion and, if necessary, be held fast in this

position by a rotatable cam *e*. The operating knob *f* of the cam, which knob is located outside the casing, has a marking line *g* which indicates the position of the cam *e* at any particular time. The stop projection *c*₂ of 55 the stop disk *b* is impeded by the nose *h* of the hinged lever *i*, which is attached in such a way as to be swung laterally to a rotatable toothed segment *j* (Fig. 1) when exposures are to be made with the time release.

The teeth of the segment *j* engage with a gear wheel *k* (Fig. 3), to the shaft of which a ratchet *l* is attached. But on the same shaft there is also an additional disk *m*, loosely rotatable, on which there is provided a pawl *n* 65 which engages the teeth of the ratchet *l* when the latter turns in the counterclockwise direction. The disk *m* is likewise provided at its circumference with teeth *o* which engage with the gear wheel *p* on the shaft *q*. This shaft *q* further carries the escapement wheel *r* of the escapement *s*, with which there is connected the balance *t* with the spiral spring *u*. This escapement resembles in general the quite well-known arrangement in clockworks with 70 balances.

The hinged lever *i*, under the influence of the spring *v* (Fig. 2), normally rests against a stop *w* and outside the range of the stop disk *b*. If, however, the time release device is to 75 be set in action, then, in order to prepare for this method, the shaft *y* which bears the milled disk-like knob *x* and which is under the influence of a spring *z*₁, and with it a pin *z*, are turned by hand, counter to said spring and in the clockwise direction until said pin has pushed the nose *h* from engagement with the stop *w*. The shaft *y* thereupon, under the action of the spring, returns to its normal position. The spring *z*₁ that is wound around the pivot of the toothed segment *j* throws the segment *j* upward at the same moment and presses the nose *h* firmly against the projection *c*₂ that is situated thereunder. The escapement mechanism is shut off for this space of time by the pawl *n* and ratchet *l* which is driven by the gear wheel *k* and runs free in this direction of rotation.

If the release lever *d* is now released by the cam *e*, then the mechanism *a*, *b*, *c*₁, *c*₂, con-

trolled by the escapement *k* to *u*, runs down slowly until, after half a minute, for example, the projection *c*₂ of the stop disk *b* slides off from the nose *h* of the hinged lever *i* and the unimpeded running-off of the mechanism for the exposure takes place.

The parts *r*, *s*, *t*, *u* have to impede the running down of the toothed segment *j*, namely in this way, that the balance *t*, in its oscillatory movements which are brought about by the spiral spring *u* as in the case of an alarm clock, allows the escapement wheel *r* to run down step by step by means of the armature *s*. This mechanism remains in motion until the nose *h* of the toothed segment *j* slides off from the stop projection *c*₂. From that moment the driving spring mechanism with the toothed disk *a* runs down freely, since the stop lever or latch lever *d* is held fast in the forced-back position by the cam *e* of the turn knob *f*. The mechanism from *h* to *u*, namely the time release, requires for its running down, according to the dimensions of the gear wheels, a space of time of about $\frac{1}{2}$ to 1 minute—i. e. from the moment at which, in consequence of the turning of the knob *x*, the nose *h* of the segment *j* remains upon the stop projection *c*₂ until it slides off from it again and, pressed sidewise by the spring *v*, engages upon the rest stop *w* where it remains until the next actuation of the knob *x*. It is clear, therefore, that during this time the operator can get to his position for the picture group that is to be taken, before the film run-off, which is likewise driven by the driving mechanism *a*, commences. This run-off must commence at that time, since the stop lever *d*, crowded to the side by *e*, *f*, *g*, is stationary, so that it cannot come into engagement with *c*₁ and *c*₂. The film run-off comes to a stop again as soon as the winding up has run down. In the case of time release exposures the latter is, of course, to amount to only a few turns.

If exposures by means of the time release, i. e. motion pictures of oneself, are to be made, the operator winds up the spring mechanism to such an extent as the scene to be taken requires (three turns of the winding crank correspond to one meter of film), turns the milled disk *x* at the upper surface of the spring mechanism in the clockwise direction until it strikes a stop, releases it again, and places the eccentrically shaped knob *f* with the line *g* upward. By means of the latter, as described, the release lever *d* is brought from the position which locks the motion picture mechanism at *c*₁, and the time release can begin to function. After half a minute, for example, the motion picture mechanism is actuated, and in the meantime one has ample time to assume the position intended in the picture.

I claim:

1. A time-controlled release mechanism for cinematographic cameras, including in com-

bination power means for operating the camera, a rotatable stop member, a driven element, an escapement mechanism for operating said driven element, a hinged lever carried by said driven element, a stop with which said hinged member is normally engaged, means to disengage said member from said stop and cause its engagement with said rotatable stop member, and manually controlled means normally engageable with said stop member to permit of the operation of said escapement mechanism and subsequent actuation of said power means.

2. A time-controlled release mechanism for cinematographic cameras, including in combination power means for operating the camera, a rotatable stop member, a driven element, an escapement mechanism for operating said driven element, a hinged lever carried by said driven element, a stop with which said hinged member is normally engaged, means to disengage said member from said stop and cause its engagement with said rotatable stop member, manually controlled means normally engageable with said stop member to permit of the operation of said escapement mechanism, said hinged lever being disengaged from said stop member after a predetermined length of time, and means for thereupon restoring said lever to engagement with said stop.

3. A time-controlled release mechanism for cinematographic cameras, including in combination a casing, power means for operating the camera within said casing, a rotatable stop member, a driven element, an escapement mechanism for operating said element, a hinged lever carried by said driven element, a stop with which said hinged lever is normally engaged, a spring-controlled shaft having a portion projecting exteriorly of said casing and operable to disengage said lever from said stop and thereby cause its engagement with said rotatable stop member, and a manually operable lever within said casing normally engageable with said stop member and operable to release the same to permit of the operation of said escapement mechanism and subsequent actuation of said power means.

In testimony whereof I affix my signature.
Professor EMANUEL GOLDBERG.
